REVERSIBLE RATCHET MECHANISM

Clifford I. Burdick, Racine, Wis., assignor to
Snap-On Tools Corporation, Kenosha, Wis., a
corporation of Delaware

Application May 19, 1945, Serial No. 594,699

5 Claims. (Cl. 192—44)

1

This invention relates to ratchet devices and more particularly to improved ratchet wrench construction for increasing the durability and service longevity thereof, although certain features thereof may be employed with equal advantage for other purposes.

It contemplates more especially the provision of an improved ratchet device construction which embodies improved friction ratchet elements that insure more dependability, durability, less wear, greater ratcheting flexibility, and extended service for devices of this character or type.

Friction ratchet wrenches of numerous types have heretofore been proposed and they embody substantially the same general elements that are subjected to excessive wear, impacts and are called upon to sustain heavy turning loads so that replacement is often found necessary. Further, in view of these unusual heavy requirements imposed upon ratchet wrenches, they are subjected to exceedingly heavy service and must soon be replaced in that the moving parts soon become worn or broken. Friction ratchets are fundamentally capable of sustaining greater loads and are subject to less wear, but have not proven too dependable in their ratcheting action.

One object of the present invention is to simplify the construction and improve the operation of devices of the character mentioned.

Another object is to provide an improved friction ratchet wrench construction which is more durable and dependable in operation.

Still another object is to provide a friction ratchet wrench construction that is more simple, durable, and less expensive from a service standpoint.

A further object is the provision of improved reversible and position control means for the pawl gripper parts of a ratchet wrench that sustains the greatest load and affords extended service without any appreciable wear thereon.

A still further object is to provide ratchet wrench with improved friction rollers and controls therefor that will sustain excessive loads for extended periods and insure dependable reversible ratcheting action.

Still a further object is to provide improved friction roller devices as improved pawl elements comprising important parts of the ratchet wrench construction.

Other objects and advantages will appear from the following description of an illustrative embodiment of the present invention.

In the drawing:

2

Figure 1 is a plan view of a device embodying features of the present invention.

Figure 2 is a fragmentary side view in elevation of the head portion of the wrench shown in Figure 1.

Figure 3 is a fragmentary view corresponding with Figure 1 having the cover plate removed to clarify the showing.

Figure 4 is a sectional view taken substantially along line IV—IV of Figure 1.

Figure 5 is a fragmentary sectional view taken substantially along broken line V—V of Figure 2.

Figure 6 is a side view in elevation of a friction pawl roller shown assembled in Figures 3 and 5.

Figure 7 is a side view in elevation of the pawl roller cage positioning lever and control.

The structure selected for illustration comprises a cast, forged or otherwise shaped body 10 which is suitably recessed to define a circular chamber 11 open on both sides for the reception of a revoluble member 12. The body 10 has an elongated handle 10' of any suitable shape formed integral therewith or otherwise attached thereto. The revoluble member 12 is retained

25 for journaled rotation within the chamber 11 of the body 10 by means of confronting face plates 13 and 14 which conform in contour with the recessed openings 15—16 communicating with the chamber 11. The cover plate 13 is sized for press-fitted attachment to the body 10 while the cover plate 14 is detachably associated with the recessed body opening 16 for retention by means of suitable fasteners 17. The fasteners 17 in this instance two, extend

35 through the face plate 14 for engagement with the body 10. The circular chamber 11 and the confronting face plate 13 provide axially aligned bores 18 and 19, respectively, to rotatively support the revoluble member 12 having axially

40 extending hubs 20 and 21. The hub 21 is appreciably smaller than the circular hub 20 of the revoluble member 12, and the former terminates in a polygonal shank 22, in this instance, square cross-section, to detachably receive 45 sockets for various nut sizes thereon.

In order to impart intermittent rotation to the revoluble member 12 responsive to oscillatory movement of the handle 10', the periphery of the hub 20 confronts friction rollers, in this instance two circumferentially spaced sets 23—24, each set 23 and 24 comprising two spaced friction rollers mounted on pins 25—26, respectively. The pins 25—26 preferably though not essentially are formed integral with the rollers 23—24 by providing annular grooves 23'—24' therein along a

transverse median line thereof (Figure 6). Each set or pair of friction rollers 23-24 are spaced on the pins 25-26 respectively, to receive a shifting cradle 27 therebetween.

The shifting cradle 27, comprises in this instance, an arcuate plate 28 having an inner curved edge 29 conforming to the curvature of an annular groove 30 provided in the periphery of the revoluble member hub 20 midway between the end surfaces thereof. The outer curved edge 31 of the cradle plate 28 (Figure 5) is described from the same axis by a larger radius than the inner curved edge 29 to afford the circumferential oscillatory displacement thereof in an elongated arcuate transverse ratcheting chamber 32 provided in the body 10 to communicate with the circular chamber 11 which confines the revoluble member 12.

The elongated arcuate ratcheting chamber 32 accommodates the friction rollers 23-24 and their shifting cradle 27 as will appear more fully hereinafter. The friction roller annular grooves 23'-24' and their communicating pins 25-26 are complements of semi-circular transverse grooves 25'-26' provided proximate to the extremities of the arcuate cradle 27. The transverse semi-circular grooves 25'-26' communicate with the outer arcuate edge 31 thereof, thereby retaining the cradle 27 within the angular grooves 23'-24' of the friction rollers 23-24, respectively. The friction rollers 23-24 contact the lower camming edges 33-34 which are also circumscribed along an arc so as to define the elongated arcuate ratcheting chamber 32 with a depth in its central region commensurate with the diameter of the rollers 23-24 to effect frictional engagement between the revoluble member 12 and the head member 10 through the rollers 23-24. These friction engaging positions between the rollers 23-24 and the camming edges 33-34, respectively, are proximate to the central region of the ratcheting chamber 32 which communicates at its center with a circular recess 35 which will be presently described. It should be noted that the elongated ratcheting chamber 32 has its greatest depth at its curved ends 36-37 so that the friction rollers 23-24 will be free from engagement with the revoluble member hub 20 and the camming surfaces 33-34 of the head member 10 when one or the other of the friction rollers 23-24 are shifted toward the ratcheting chamber enlarged ends 36 or 37. Consequently, the position of the cradle 27 within the ratcheting chamber 32 will determine whether or not the rollers 23 or 24 are engaged or wedged between the revoluble member hub 20 and the camming surfaces 33 or 34 of the head member 10.

The circular recess 35 confines a cylindrical cradle positioning trunnion 38 (Figure 7) which is milled or otherwise shaped to provide a radially extending tooth 39 having converging side surfaces 40-41 to cooperate with a spring impelled detent 42. The spring impelled detent 42 consists, in this instance, of a spherical ball which is confined in a longitudinally extending bore 43 having a spring 44 disposed therein below the spherical detent 42. The spherical detent 42 is urged in the direction of the trunnion tooth 39 for engagement with one or the other of the converging surfaces 40-41 to maintain the trunnion 38 in one or the other of two operable angular positions.

The trunnion 38 controls the position of the friction roller cradle 27 through the median of a

substantially U-shaped trip member 45 that is embodied in the cylindrical surfaces of the trunnion 38 diametrically opposite the tooth 39 therein. The U-shaped trip member 45 projects from the trunnion 38 to register with a slot 46 provided in the friction roller cradle 27 to communicate with the outer arcuate edge 31 thereof. The radial position of the trunnion 38 determined by the surface 49 or 41 of the tooth 39 that is engaged by the spring impelled detent 42, will control the position of the friction roller cradle 27 and the respective rollers 23 or 24.

The position of the friction roller cradle 27 determines which rollers 23 or 24 are frictionally wedged between the revoluble member 12 and the camming surfaces 33 or 34. This, in turn, determines the direction of friction roller ratcheting of the revoluble member 12 responsive to oscillatory movement manually imparted to the handle 10'. In order to radially shift the positioning trunnion 38 and thus control the direction of ratcheting which is determined by the position of the friction roller cradle 27, an externally accessible finger manipulating lever 47 is fixed to the trunnion 38. To this end, the lever 47 has one end 48 thereof of reduced depth for mounting in a slot provided diametrically through the end 50 of the trunnion 38. This reduced lever end 48 is fixedly attached to the trunnion 38 to impart the desired rotary movement thereto. Consequently, the direction of ratcheting can be controlled with the finger manipulating lever 47 as will appear more fully hereinafter.

It should be noted that the body 10 is inwardly offset as at 51 (Figure 2) in the intermediate shank region 52 to accommodate the trunnion positioning lever 47 so that the inwardly offset reduced end 48 thereof will project beneath the face plate 14 and the top edge of the lever 47 will be in the plane thereof (Figure 2). The confronting face plates 13-14 extend over the circular recess 35 to confine the trunnion 38 in the bore 35, thereby maintaining the revoluble member 12 and all of its ratcheting control elements assembled within the body 10.

With the arrangement of parts above described, any suitable device for turning such as wrench sockets (not shown) may be detachably or otherwise associated with the revoluble member 12. In the present embodiment, the shank 22 extends axially from the revoluble member 12, it being preferably though not essentially provided with a spring impelled detent 22' of standard construction so that wrench sockets having variously sized openings or other fastener turning accessories may be detachably associated therewith. The manual trunnion adjusting lever 47 may be provided for adjustment relative to suitable indicia, in this instance, directional "on" and "off" indicators 53 and 54 inscribed on the external face of the body 10.

Displacement of the friction roller cradle 27 in a counter-clockwise direction (viewed from Figure 3 occasioned by displacing the lever 47 to "on" position, will cause the friction rollers 23 to engage the periphery 26 and the camming surface 33 for wedged insertion therebetween for urging the revoluble member 12 in a corresponding direction to tighten or engage a right hand threaded member. While the cradle 27 is in this position, the friction rollers 24 are positioned in the enlarged end region 37 of the ratcheting chamber 32 where they are free from engagement and thus inoperative.

Opposite lever displacement indicated by di-

rectional indicator "off" places the friction rollers 24 in engagement with the revoluble member 12 to loosen a correspondingly threaded fastener or member, thereby enabling the friction rollers 23—24 serving as ratchets to function in opposite directions with but a single control lever 47 easily adjusted for the purpose set forth. The directional ratcheting is controlled by manipulating the lever 47 so that fasteners such as nuts can be turned "on" and "off" and the extent of each bite or intermittent rotation of the revoluble member 12 will depend upon the ratcheting stroke which is within the control of the attendant.

While I have illustrated and described a preferred embodiment of this invention, it must be understood that the invention is capable of considerable variation and modification without departing from the spirit of the invention. I, therefore, do not wish to be limited to the precise details of construction set forth, but desire to avail myself of such variations and modifications as come within the scope of the appended claims.

I claim:

1. In a ratchet mechanism, the combination with a body member, of a revoluble member journaled in said body member, said members comprising intermittent driving and driven elements, there being an elongated arcuate chamber in said body member communicating with said revoluble member to present integral camming surfaces toward and from said revoluble member, elongated arcuate carrier means mounted for displacement within said body member camming chamber, said camming chamber and carrier extending for a circumferential portion of said revoluble member, friction rollers rotatively mounted in the extremities of said carrier means for circular displacement therewith in opposite directions to engage and disengage said revoluble member, the camming surfaces of said elongated chamber terminating in enlarged ends for receiving said friction rollers when said carrier is shifted to one extreme position or another to disengage the friction rollers displaced thereto and engage the friction rollers displaced therefrom, means associated with said friction carrier means for shifting said friction rollers along said camming chamber in operative and inoperative engaging relation with said revoluble member, and means operatively connected with said shifting means to maintain the latter in one or the other of its extreme displaceable positions.

2. In a ratchet mechanism, the combination with a body member, of a revoluble member journaled in said body member, said members comprising intermittent driving and driven elements, there being an elongated arcuate chamber in said body member communicating with said revoluble member to present integral camming surfaces toward and from said revoluble member, elongated arcuate carrier means mounted for displacement within said body member camming chamber, said camming chamber and carrier extending for a circumferential portion of said revoluble member, friction rollers rotatively mounted in the extremities of said carrier means for circular displacement therewith in opposite directions to engage and disengage said revoluble member, the camming surfaces of said elongated chamber terminating in enlarged ends for receiving said friction rollers when said carrier is shifted to one extreme position or another to disengage the friction rollers displaced thereto and engage the friction rollers displaced therefrom, means associated with said friction carrier means

for shifting said friction rollers along said camming chamber in operative and inoperative engaging relation with said revoluble member, and friction means operatively associated with said shifting means to maintain the latter in one or the other of its extreme displaceable positions.

3. In a ratchet mechanism, the combination with a body member, of a revoluble member journaled in said body member, said members comprising intermittent driving and driven elements, there being an elongated arcuate chamber in said body member communicating with said revoluble member to present integral camming surfaces toward and from said revoluble member, elongated arcuate carrier means mounted for displacement within said body member camming chamber, said camming chamber and carrier extending for a circumferential portion of said revoluble member, friction rollers rotatively mounted in the extremities of said carrier means for circular displacement therewith in opposite directions to engage and disengage said revoluble member, the camming surfaces of said elongated chamber terminating in enlarged ends for receiving said friction rollers when said carrier is shifted to one extreme position or another to disengage the friction rollers displaced thereto and engage the friction rollers displaced therefrom, means associated with said friction carrier means for shifting said friction rollers along said camming chamber in operative and inoperative engaging relation with said revoluble member, a trunnion fixed to said shifting means to effect the pivotal mounting thereof in said body member, and means for maintaining said trunnion in extreme opposite pivotal positions to control the direction of ratcheting said revoluble member.

4. In a ratchet mechanism, the combination with a body member, of a revoluble member journaled in said body member, said members comprising intermittent driving and driven elements, there being an elongated arcuate chamber in said body member communicating with said revoluble member to present integral camming surfaces toward and from said revoluble member, elongated arcuate carrier means mounted for displacement within said body member camming chamber, said camming chamber and carrier extending for a circumferential portion of said revoluble member, friction rollers rotatively mounted in the extremities of said carrier means for circular displacement therewith in opposite directions to engage and disengage said revoluble member, the camming surfaces of said elongated chamber terminating in enlarged ends for receiving said friction rollers when said carrier is shifted to one extreme position or another to disengage the friction rollers displaced thereto and engage the friction rollers displaced therefrom, means associated with said friction carrier means for shifting said friction rollers along said camming chamber in operative and inoperative engaging relation with said revoluble member, a trunnion fixed to said shifting means to effect the pivotal mounting thereof in said body member, rotary position indexing means provided on said trunnion, and spring impelled means in said body member for cooperating with said trunnion indexing means to maintain said friction rollers in one or the other of their extreme displaceable positions.

5. In a ratchet mechanism, the combination with a body member, of a revoluble member journaled in said body member, said members comprising intermittent driving and driven elements,

there being a chamber in said body member communicating with said revoluble member to present integral camming surfaces toward and from said revoluble member, carrier means mounted for circular displacement in opposite directions within said body member camming chamber, and friction rollers rotatively mounted in said carrier means for displacement therewith in opposite directions to engage and disengage said revoluble member, said carrier means being of lesser length than and shaped to conform with said camming chamber for movable association with said friction carrier means for shifting said friction rollers along said camming chamber in operative and inoperative engaging relation with said revoluble member.
